DESIGN FOR AN EMBROIDERED WEBBING

Charles Stern, West New York, N. J.

Application April 23, 1934, Serial No. 51,490

Term of patent 3½ years

To whom it may concern:

Be it known that I, CHARLES STERN, a citizen of the United States of America, residing at West New York, in the county of Hudson and State of New Jersey, have invented a new, original, and ornamental Design for an Embroidered Webbing, of which the following is a specification, reference being had to the accompanying drawing, forming part thereof and in which:

The figure is a plan view of a piece of embroidered webbing, showing my new design.

I claim:

The ornamental design for an embroidered webbing, as shown.

CHARLES STERN.
